UNITED STATES PATENT OFFICE.

SARA WEBER MCCORMICK AND HUGH MALCOLM MCCORMICK, OF CHICAGO, ILLINOIS,
ASSIGNORS, BY MESNE ASSIGNMENTS, TO CHAMPION CORSET COMPANY, OF YPSI-
LANTI, MICHIGAN, A CORPORATION OF MICHIGAN.

METHOD OF DESIGNING CORSET ABDOMINAL SUPPORTS.

Application filed March 30, 1918. Serial No. 225,642.

set and is otherwise located as follows: Commencing at the true waistline, one-half an inch inside front or clasp edge, measure diagonally downward nine inches to a point 5 two inches inside front edge of the corset for sizes 18 to 22, inclusive; and, similarly, in size 23, $9\frac{1}{4}$ inches; in size 24, $9\frac{1}{2}$ inches; in size 25, $9\frac{3}{4}$ inches; in size 26, 10 inches; in size 27, $10\frac{1}{4}$ inches; in size 28, $10\frac{1}{2}$ inches; 10 in size 29, $10\frac{3}{4}$ inches; in size 30, 11 inches; in size 31, $11\frac{1}{4}$ inches; in size 32, $11\frac{1}{2}$ inches; in size 33, $11\frac{3}{4}$ inches; in size 34, 12 inches; in size 35, $12\frac{1}{4}$ inches; in size 36, $12\frac{1}{2}$ inches. On corsets of ordinary construction the foregoing measurements will locate point 3 below the lower end of the front clasp as shown in Fig. 1. Point (4) is also located adjacent to the seam in question and is about two inches lower than point (3). A sheet 15 of paper or other suitable material (P), Figure 2, is then placed over the corset and the points 1, 2, 3, 4, marked thereon, preferably by passing thumb tacks through the paper and through the points 1, 2, 3, 4, previously located on the corset.

After outlining the first general dimensions of belt on sheet of paper (P), Figure 3, draw line (e) Figure 4, parallel to and one-half inch below base line (b), front end of 20 line (e) being one-half inch inside front edge (c). The position of line (f) above and parallel to base line (b) is approximately one and one-half inches for the smaller sizes of belts, and as much as two 25 and one-half inches, for the larger sizes. The distance of line (f) above line (b) must now be accurately noted by the designer in each instance as its final position is often changed, as will be hereinafter described. 30 Lines (e) and (f) serve as guides in drafting the first lower outline (k) of the abdominal support. Line e indicates the position occupied by the lower end of the stiffener-plate, when the lower front corner of section A is being drafted. Line f is drawn 35 across the lower part of section B beginning at a point about one-half inch inside the rear edge thereof and continuing to a point about one-half inch from the front edge of 40 said section.

50 A stiffener plate (g), made preferably of aluminum, is now positioned as in Figure 4 with its lower end (hh) on line (e) and front edge (h) at point (u) one-half inch from line (c). Outline lower front corner along edges (h), (hh), thence continuing bottom line (k) to point (z). Draw top curved line (i). The extreme depth of its 55 curve below first diagram line (a) varies from one-half of one inch to one and one-half inches, according to length. Draw 60 grading-line (j) laterally across middle of pattern. Cut out pattern on lines (i), (c), (h), (hh), (k) and (d) and separate into 65 three preliminary-pattern sections A, B, and

C, on lines (16) and (17) preferably having section B wider and section (C) narrower than section A.

In Fig. 4, grading line j is a straight line drawn laterally across sections C, B and A 70 bisecting lines 17—16 approximately half-way between the top line i and the bottom line k, commencing at line d and terminating at line e.

A good proportion for the widths of the 75 sections of abdominal supports is to have section A one and one-half times, and section B twice as wide as section C, but these proportions need not necessarily be exact.

Line f, in Fig. 4, positively fixes the height 80 of curved line k, in the first draft of the abdominal support pattern, and in the final drafting of the lower line s, Fig. 8, line f constitutes an accurate guide for determining the height of the curve at different tangents. Line s is always a free-hand 85 line, and line f is so placed on patterns of different sizes as to form a base from which to estimate the height of the curved line s on the final or master-pattern sections. Such 90 a base to work from makes uniform and accurate drafting of lower lines of abdominal supports possible.

In the process of designing, abdominal 95 support, sections must bear some definite relation to one another at one point, and the function of grading line j is to enable the designer to assemble master-pattern sections A, B and C in correct relation to each other, preparatory to drafting final upper 100 and lower lines thereof. This relation is obtained by placing said sections so that line j of section B is in lineal contact with line j of sections A and C, in Figs. 8 and 9, when said sections are ready for said final 105 drafting of said final upper and lower curved lines. The various additions to, and parts taken from, said sections, in the process of designing, so alter the positions of the original top and bottom lines, with respect to each other after the original pattern 110 is separated into sections and said sections are modified that, until the present system of working from said central grading line was perfected, pattern-designing was 115 uncertain and inaccurate.

Outline preliminary-pattern sections A, B, C, Figure 5, on an additional sheet of paper, separated sufficiently to permit enlargements, and transcribe in proper places line (f), 120 grading-line (j) and points (u) and (z). Add five-eighths of one inch (L) to rear edges of sections A and B, and one-half inch (M) to rear of section C for seam allowances. Measure three-eighths of one inch 125 back from lower rear corner (99) of section B, and draw line (O) from this point to upper rear corner (98). Similarly measure three-eighths of an inch forward from lower front corner (96) of section C and draw line 130

(O) from this point to upper front corner (94). Lines (O), (O) are usually straight as shown, but are better in some models of corsets if slightly convex.

- 5 Mark points (25), (30) Figure 1, on corset one-half inch above point (1) and one-half inch below point (4) and place ruler (60) with edge in contact with these points, and in front of line of attachment (40) of belt to corset. Draw corset so that the portion underneath the ruler lies flat and straight. Note size and shape of that part of corset (NN) between edge of ruler and line of attachment (40) of the belt to the 10 corset, said line following the front edge of the stripping which is located about half way between the side and the rear of the corset, and add a similarly sized and shaped segment (n), Figure 5, to rear of section C.
- 15 Extend grading-line (j) across seam allowances and segments.
- 20 Measure forward from lower rear corner 91 of section A, Figure 5, the amount (p) to be taken off for goring, as follows: sizes 25 18-22, $\frac{1}{8}$ inch; size 23, $\frac{3}{16}$ inch; size 24, $\frac{1}{4}$ inch; size 25, $\frac{5}{16}$ inch; size 26, $\frac{3}{8}$ inch; size 27, $\frac{7}{16}$ inch; size 28, $\frac{1}{2}$ inch; size 29, $\frac{9}{16}$ inch; size 30, $\frac{5}{8}$ inch; size 31, $\frac{11}{16}$ inch; size 32, $\frac{3}{4}$ inch; size 33, $\frac{13}{16}$ inch; size 34, $\frac{7}{8}$ inch; size 35, $\frac{15}{16}$ inch; size 36, 1 inch. Find similar amount on graduated guide, Figure 6, and place guide at this point over point (p) on section A, Figure 7, having upper part of front edge (77) of guide even with upper 35 part of rear edge (LL) of section, and draw outline. Similarly measure back from lower front corner (92) of section B, Figure 5, the same amount of goring (p), and, reversing guide, proceed, Figure 7, the same as with section A. Cut new front and rear outlines of master-pattern sections A, B and C.

- 40 Mark points 31, 32, 33, Figure 8, on top, grading and bottom lines of section C, five-eighths of an inch from front edge 102. Likewise, mark points 31, 32, 33 on top, grading and bottom lines of section B, five-eighths of an inch from front edge 101. Lap rear edge 103 of section B at grading-line (j) over front edge 102 of section C to point (32) and insert thumb tack (R) on grading-line (j) five-sixteenths of an inch from rear edge 103 of section B through both patterns into table. Similarly lap section A over section B at grading-line (j) to point 32 and insert thumb tack (R) on grading-line (j) five-sixteenths of an inch from rear edge 100 through both patterns into table. Adjust section C underneath section 55 B to points 31, 33 and fasten with thumb tacks R to table. Swing lower part of section A over section B to point 33 and put thumb tack R through both sections into table. Check, and if necessary, alter the final position of line f. This is done by

measuring against the distance between base line b and original line f (Fig. 4), a distance equal to one and one-half inches plus one-half the amount the distance between points u and z exceeds eleven inches. The 70 difference between these two measurements, if any, is laid off above original line f of the assembled-master-pattern section B (Fig. 8), and a new or final line f is drawn there-thru parallel to original line f. Ordinarily 75 if the distance between points u and z does not exceed eleven inches the original and final positions of line f will be the same.

For example if original line f was $1\frac{3}{4}$ " 80 above base line b and points u and z are 13 inches apart, the final position of line f will be $\frac{3}{4}$ " above the original position.

After thus fixing the final position of line f the bottom line s defining the bottom edges 85 of the master-pattern sections is drawn and the bottom edges of the sections are cut thereon.

Because the increased amount of goring taken from the lower part of the meeting edges of sections A and B with each increase 90 in size changes the relative positions of sections A and B to each other, when positioned for final drafting of curved lower line (s) Figure 8, of belt, said line (s), in small size belts intersects and passes above line (f) 95 but the arc above line (f) is lowered proportionately with each succeeding increase in length until, in the larger sizes, as shown in Figure 9, it may be tangential to line (f) 100 near the rear lower edge of section B.

After the bottom edges of the master-pattern sections are thus obtained the sections are turned about points 32 until the rear edges of sections A and B are over points 31. The final line t, defining the 105 top edges of the master-pattern sections, is drawn and the top edges of the sections are cut thereon. Line t is produced by drawing a substantially smooth continuous curve 110 guided by the fragments of line i.

The three master-pattern sections thus produced may be used as the guides for cutting the support material into corresponding sections which are sewed together to produce a half-support such as shown in 115 Fig. 10.

The graduated guide, Figure 6, was devised to overcome the lack of uniformity in curving the rear edge of section A and the front edge of section B of belts made by different designers, and even of those made by the same designer. By its use, patterns are evenly curved and correctly and uniformly gored according to size.

In belts for small sizes of corsets where the triangular additions (vv), (vv) Figure 7, to meeting edges of sections B and C are wider than the gores (pp), (pp) taken from the lower meeting edges of sections A and B, the front lower corners of the belt are 125 130

raised above the position 3, Figure 1, first diagrammed for them on the corset. This is corrected in drafting patterns by marking said lower front corner belt positions on the corset from one-eighth to one-half of an inch lower (depending on the difference in width between the segments (vv) , (vv)) added to sections C and B, and the gores (pp) (pp) taken from sections (B and A) than the belt is to occupy, and taking off a like amount 90, Figure 9, from the top of section A when drafting final upper line (t) of the belt.

Additions to sections C and B often cause the top front corner 97 of section A, Figure 9, to occupy a position too near the front edge (w), Figure 10, of the corset. This is corrected by cutting off the triangular segment 93, Figure 9, from the front of section A, as follows: Measure back from front upper corner 150 along top of section A from one-eighth of one inch to one-half of one inch as required, and from thence draw a convex line 95 downward to meet the front line (e) at a point 110, from two to four inches below the new front corner 115.

In some models of corsets, the belts give better results if small curved triangular gores (41), (41) Figure 7, are taken from the meeting edges of the upper parts of sections B and C, but care must be taken not to make the upper part of the belt tight enough to bind.

Referring to Figure 7, for thin figures where the crest of the ilium and particularly the anterior superior spine of the ilium is proportionately prominent compared with the adjacent abdomen, extra belt fullness should be added (5), (5), by slightly con vexing the central meeting edges of sections B and C, to allow comfortable additional fullness over the hip bone.

Referring to (3), Figure 1, the average lower front corner belt position is two inches inside the front edge (w). This position, however, must vary somewhat in proportion to the fullness of the skirt of the corset (29) and, in models in which the proportionate skirt fullness increases with size of corset, said lower front corner belt position should correspondingly recede.

While the lower maximum width of the triangular additions (vv) , (vv) , Figure 7, to the front of section C and the rear of section B is given herein as three-eighths of an inch for all sizes of corsets, it is better in some models of corsets to add wider segments, but, in so doing, the position of the lower front corner of the belt 3, Figure 1, must be considered in order that the belt be not made too long. Also these triangular segments, if wider, raise the front of the belt and must be allowed for in diagramming the position of point 3, Figure 1, on the corset.

In designing belts for figures where the full part of the abdomen is higher than normal and recedes abruptly, the normal position of a regular stock belt, as diagrammed by points 1, 2, 3, 4, Figure 1, is marked on the corset, but wider gores (pp) , (pp) , Figure 7, are taken from sections A and B, and the difference between such increased width and the width of gores in an average belt for the same corset is added to the distance between points (u) and (z), Figure 8, in determining the final position of line (f).

The belt V, Figure 10, may be attached comparatively farther forward in large sizes of corsets than in small and medium sizes. Such belts are more satisfactory than those which are proportionately too long for their depth. Proportions for average models are those shown in Figures 8 and 9, which are drawn to scale for sizes twenty and thirty-one respectively.

When properly designed and positioned in a corset, the front edge (55) of the middle or full part of the belt V, Figure 10, when stretched taut and raised slightly, should be a little over one-half of one inch back from the front edge (w) of the corset. In corset abdominal supports thus produced the front lower portions thereof will usually be below the lower ends of the front clasps of the corsets when said abdominal supports are attached to ordinary corsets.

Abdominal supports are designed to complement corsets, and it is always assumed that the corset will be the proper size and style for the wearer, and that the waistline of the corset (6) Figure 1, will be at her waistline, for, in designing belts all downward measurements are taken from the waistline, and the belts in a corset which sets too high on the wearer's figure, will not be low enough to give her the best results.

Referring to Figure 1, abdominal support corsets give better figures and greater comfort to their wearers if their clasps (wv) and groin boning (y) are shorter below the waist than in ordinary corsets, as this permits the front of the corset skirt to more closely follow the contour of an abdomen reduced by abdominal supports.

Having thus described our invention, what we claim as new and desire to secure by Letters Patent of the United States is:

1. The method of designing one-half of an intra-pelvic abdominal support for use with corsets, which includes the steps of outlining on suitable material a four sided figure defined by four points plotted on a corset indicating a grading line on the figure, separating the figure into a plurality of preliminary-pattern sections, using the preliminary-pattern sections to outline on another piece of material corresponding master-pattern sections which are modified by seam and shaping allowances and indicating a

corresponding grading line, cutting the side edges of the master-pattern sections, assembling the master-pattern sections according to the grading line and with adjacent side edges overlapping, rotating the master-pattern sections about points on the grading line to alternately vary the over-lap at the top and at bottom thereof, and cutting the top and bottom edges of the master-pattern sections in the respective positions.

2. The method of designing a master-pattern for use in the production of intra-pelvic abdominal supports for corsets which includes the steps of outlining on suitable material a four sided figure defined by four points plotted on a half corset and having the upper and lower sides curved, dividing the figure by a grading line, separating the figure transversely of the grading line into a plurality of preliminary-pattern sections each section including a part of the grading line, cutting from another piece of material a corresponding set of master-pattern sections whose longitudinal edges are defined by the preliminary-pattern sections and seam and shaping modifications, and which include corresponding grading line parts, assembling the master-pattern sections with the grading line parts overlapping at adjacent edges, and defining the upper and lower edges of the master-pattern sections while said sections are thus assembled.
3. The method of designing master-pattern sections with which to produce intra-pelvic abdominal supports for corsets which consists in outlining on suitable material a four sided figure defined by datum points plotted on a half corset, dividing the figure by a grading line passing across its mid-section, separating the figure transversely of its grading line into a plurality of preliminary-pattern sections each of which contains a part of the grading line there-across, trans-

ferring the preliminary-pattern sections including grading line to another sheet of material and outlining the same thereon with modifying seam and shaping allowances at the sides, cutting the sides of the master-pattern sections along the sides of the modified outlines, assembling the master-pattern sections with the grading line parts thereon overlapping at adjacent edges, alternately overlapping the upper and lower portions of the master-pattern sections by predetermined amounts, and shaping the opposite ends of the master-pattern sections in the alternate positions.

4. The method of producing intra-pelvic abdominal supports for use with corsets, which includes the steps of outlining on suitable material a four sided figure defined by four points plotted on a corset, defining a grading line across the figure, separating the figure into a plurality of preliminary-pattern sections, using the preliminary-pattern sections to outline on another piece of material corresponding master-pattern sections which are modified by seam and shaping allowances and to define a corresponding grading line on such master-pattern sections, cutting the side edges of the master-pattern sections, assembling the master-pattern sections according to the grading line thereof and with adjacent side edges overlapping, defining the top and bottom edges of the master-pattern sections when thus assembled, cutting support sections from suitable support material on the final outlines of the master-pattern sections, and joining together sets of support sections in the relation of the assembled master-pattern sections.

March 27, 1918.

SARA WEBER McCORMICK.
HUGH MALCOLM McCORMICK.
